Des. 213,402
Patented Feb. 25, 1969

213,402

CARPET STRETCHER

Roy L. Brenner, Highland Park, Ill., assignor to Kinkead
Industries Incorporated, Chicago, Ill., a corporation of Illinois

Filed Apr. 5, 1968, Ser. No. 11,318

Term of patent 14 years

U.S. Cl. D54—13
Int. Cl. D8—02

FIG. 1

FIG. 4

FIG. 5

FIG. 2

FIG. 3

FIG. 2 is a top view, foreshortened for convenience of illustration;

FIG. 3 is a right side elevational view, foreshortened for convenience of illustration;

FIG. 4 is a front elevational view; and

FIG. 5 is a back elevational view.

I claim:

The ornamental design for a carpet stretcher, substantially as shown and described.
